UNITED STATES PATENT OFFICE.

ERNEST C. EVERETT, OF NEW YORK, N. Y., ASSIGNOR TO R. E. DIETZ CO., OF NEW YORK, N. Y.

BURNER-SHAFT HANDLE.

1,247,804.

Specification of Letters Patent. Patented Nov. 27, 1917.

Application filed March 16, 1917. Serial No. 155,324.

To all whom it may concern:

Be it known that I, ERNEST C. EVERETT, a citizen of the United States, residing at New York, in the county of New York and 5 State of New York, have invented a new and useful Improvement in Burner-Shaft Handles, of which the following is a specification.

This invention relates to wick raiser devices for use on various types of lamps and lanterns, and has for one object to provide 10 a device of this character of simple and efficient construction, which can be inexpensively manufactured, and by means of which 15 fine adjustment of the wick of a lamp or lantern can be effected.

Another object of the invention is to provide a device of this sort which can be readily used in connection with tension means 20 of the kind commonly employed for preventing the wick shaft from being turned by accidental jarring or striking of the lamp or lantern on which it is mounted.

Other objects and advantages of the invention are hereinafter described.

In the accompanying drawings:

Figure 1 is a front elevation of the lower portion of a tubular lantern provided with a wick raising mechanism embodying the 30 invention.

Fig. 2 is a fragmentary elevation thereof on an enlarged scale showing the finger piece of the wick raising mechanism and the tension means therefor.

Fig. 3 is an elevation of the wick raiser shaft detached from the lantern.

Fig. 4 is a rear elevation of a driving or carriage lamp having the wick raising mechanism mounted thereon.

Fig. 5 is a side elevation of the lower portion of a railway lantern, showing the preferred arrangement of the wick raising mechanism and tension means thereon.

Fig. 6 is a fragmentary top plan view 45 partly in section of the construction shown in Fig. 5, the oil font being shown removed from the lantern.

Fig. 7 is a side elevation of another arrangement of the wick raiser device and 50 tension means on a railway lantern.

Fig. 8 is a fragmentary top plan view, partly in section, of the construction shown in Fig. 7.

Referring to Figs. 1-3, 9 represents the 55 oil font of a tubular lantern, having tubes

10, air chamber 11, and globe plate 12, of well known construction. 13 is a wick raiser shaft which is mounted on the lantern in the usual way, and preferably has the toothed wheels or disks 14 secured thereon and 60 adapted to engage with the lantern wick to raise or lower the same when the shaft is turned. Any other suitable means for connecting the wick and the raiser shaft can be utilized if desired, in place of the wheels 65 or disks 14.

The finger piece or operating member of the shaft 13 is formed by bending the end of the shaft to form a substantially annular or circumferential rim portion 16, lying in 70 a plane at right angles to the plane of the wick raiser shaft 13, the rim portion 16 being joined with the wick raiser shaft by means of a radially bent portion 17 lying substantially in the plane of the annular rim 75 portion. This method of forming the finger piece on the wick raiser shaft is extremely economical, the wick raiser shaft 13 being constructed of wire which can be readily bent into the desired shape, and the possibility of the finger piece becoming detached from the shaft, as is often the case when the parts thereof are formed separately is eliminated. The extremity of the portion forming the rim 16 is preferably connected with 80 the adjacent surface of the radially bent portion 17. In the manufacture of the burner shafts, it is customary after the shafts are formed, to dip them in melted tin, in order to give a non-rusting finish. 90 During this operation, enough tin adheres to the shaft to close the joint between the extremities of the rim portion 16 and the adjacent surface of the radial portion 17, as indicated at 16a. In this way a stronger 95 construction results than is the case when the portions mentioned are not connected. The circular form of the finger piece being in a plane transverse to that of the shaft aids the operator materially in effecting any 100 desired adjustment of the lamp wick and there are no protruding points on the finger piece to catch in the clothing of the operator.

In order that the wick raiser shaft may 105 not be turned by accidental jolting or jarring of the lantern, tension means are preferably provided which may be mounted on any desired part of the lamp or lantern, and which bear against the finger piece and fric- 110

tionally hold the shaft against accidental displacement. The preferred form of tension means comprises a metal strip or spring 18, which as used on a tubular lantern, is 5 suitably curved and has one end thereof secured to the globe plate 12 in any usual manner and the other end bearing against the inner side of the rim 16 of the finger piece. The strip exerts sufficient spring 10 pressure against the finger piece to prevent the shaft from being moved accidentally, and yet does not interfere with rotation of the shaft and finger piece by hand.

When the device is used in combination 15 with a carriage lamp, as shown in Fig. 4, the tension strip 19 is mounted on the rear casing 20 of the lantern, and bears against the inner surface 21 of the finger piece 22 in the same way as when used on the tubular 20 lantern.

Referring to Figs. 5-8, which show a wick raiser mechanism and tension means used in connection with a well known form of railroad lantern, 23 represents the upper 25 right lantern guards which are secured to a horizontal flat ring guard 24 and to another ring guard 25. 26 is the body hoop of the lantern and 27 is the oil font. All these parts are well known in the art. Figs. 5 30 and 6 show the preferred arrangement of the tension means on the lantern. In the construction shown in these figures the strip 28 is secured in any well known way to the outside wall of the font 27 and is of suitable 35 curvature so as to bear against the inner surface of a finger piece 29, formed at the end of the shaft 30 as aforescribed.

Figs. 7 and 8 show another form in which the invention may be applied to a railroad 40 lantern. In the construction shown in these figures, one end of the curved tension strip 31 is attached to the guard ring 24 of the lantern in any suitable manner, and the opposite end of said strip bears against the rim 45 32 of the finger piece.

Copies of this patent may be obtained for five cents each, by addressing the "Commissioner of Patents, Washington, D. C."

29^a represents the joint which is preferably formed between the extremity of the rim portion of the finger piece, and the adjacent surface of the radially bent portion of the shaft. Such joint is preferably 50 formed while the shafts are being tinned, as heretofore described.

I claim as my invention:—

1. In a wick raiser mechanism for lanterns, a rotatably mounted wire wick-raising shaft having one end thereof bent and forming a substantially annular finger-piece disposed substantially concentric with said shaft and in a plane at substantially right angles to the plane of the shaft, and a connecting portion which joins said annular finger piece to said shaft and is integral with said shaft and said finger piece.

2. In a wick raiser mechanism for lanterns, a wire shaft having one end thereof bent into substantially annular form in a plane at substantially right angles to the plane of the shaft and having a radial portion connecting said annular portion with said shaft, said radial portion being formed 70 integral with said shaft and said annular portion.

3. In a wick raiser mechanism for lanterns, a wire shaft having one end thereof bent into substantially annular form in a 75 plane at substantially right angles to the plane of the shaft and having a radial portion connecting said annular portion with said shaft, said radial portion being formed integral with said shaft and said annular 80 portion, and the extremity of said shaft being secured to the adjacent surface of said radial portion.

Witness my hand this 12th day of March, 1917.

ERNEST C. EVERETT.
